THE NORRIS PICTERS CO., PHOTO-LITHO., WASHINGTON, D. C.

UNITED STATES PATENT OFFICE.

ALFORD ALVIN GOHN, OF GLADERUN, PENNSYLVANIA.

BARREL-HEATER.

SPECIFICATION forming part of Letters Patent No. 745,432, dated December 1, 1903.

Application filed April 4, 1903. Serial No. 151,167. (No model.)

To all whom it may concern:

Be it known that I, ALFORD ALVIN GOHN, a citizen of the United States, residing at Gladerun, in the county of Warren and State 5 of Pennsylvania, have invented a new and useful Barrel-Heater, of which the following is a specification.

This invention is an improved barrel-heating device, the object being to provide a simple and highly-efficient construction of barrel-heater which is so constructed that in operating the same it will not be necessary to lift the barrels over the burner when placing or removing the barrels.

Another object of the invention is to provide a heater using gas and one which will automatically operate to cut the gas off and on as required, thereby economizing in the use of the gas, inasmuch as it is only consumed to any considerable extent when the barrel is being heated.

A still further object is to provide a barrel-heater in which the operation of a single lever will be sufficient to effect the operation 25 of all the other various parts of the apparatus.

With these objects in view my invention consists, essentially, in the employment of a bed-plate having an opening in the bottom thereof, a burner located beneath the bed-plate and adapted to be projected through the opening therein, a case arranged beneath the bed-plate and in which the swinging burner moves, an igniter arranged in connection with the said case by means of which the 35 burner is lighted as it passes upwardly through the opening in the bed-plate, a hood arranged upon the bed-plate and within which the barrel to be heated is placed, said hood having a door at the forward side thereof, 40 together with means for raising and lowering the burner, cutting on and off the gas, and raising and lowering the door of the hood.

The invention consists also in certain details of construction and novelties of combination whereby the various objects before referred to are accomplished.

In the drawings forming part of this specification, Figure 1 is a detail perspective view of a barrel-heater constructed in accordance 50 with my invention. Fig. 2 is a vertical sectional view of the heater, the door-operating mechanism being omitted. Fig. 3 is a hori-

zontal sectional view on the line 3 3 of Fig. 2. Fig. 4 is a detail sectional view taken through a portion of the upper end of the hood. Fig. 55 5 is a detail view, partly in plan and partly in section, showing the manner of arranging the doors at the front of the hood and jacket. Fig. 6 is a detail plan view, partly in section, showing the manner of arranging the burner 60 and pipe, the igniter, and the manner of connecting the burner and igniter pipes to the gas-supply pipe and also the case for containing the burner when not in operation. Fig. 7 is a detail perspective view showing 65 the arrangement of the valves for controlling the gas-supply. Figs. 8 and 9 are detail sectional views of the igniter and burner valves, respectively. Fig. 10 is a detail view illustrating the sliding plate through which the 70 burner-pipe passes and which closes the rear end of the case for the said burner.

In constructing a barrel-heater in accordance with my invention I employ a bed-plate A, which has an elongated opening A' produced therein and also a small circular opening A², adjacent the elongated opening A'. A hood B is arranged upon the bed-plate and is of such size that the barrel to be heated can be conveniently located therein, and when 75 the barrel is arranged within the hood and rests upon the bed-plate it will encompass the openings A' and A², as most clearly shown in Fig. 2, and it will of course be understood that at the time the barrel is heated it is open 80 at one or both ends. The hood B is open at the front and is provided with a vertically-sliding door B', said door sliding between the upright guiding-standards B², which are connected to the forward corners of the hood and 85 extend a considerable distance above the same. If desired, a jacket C may be arranged within the hood depending from the top thereof, and when such jacket is employed in connection with the hood it also is provided with an 90 upwardly-sliding door C', suitable guiding-standards being arranged adjacent and in parallel relation to the standards B², and the sliding bars B' and C' are connected by means of a strip C², which effectively closes the hood 95 when the doors are lowered, said strip being of sufficient width to engage the top of the hood, as most clearly shown in Figs. 2 and 5. This strip also forms the connecting means

between the doors B' and C', so that when one door is raised the other door will raise also and likewise when lowering.

The doors are raised by means of a cable D, which passes over a pulley D', journaled in a bracket D², arranged upon the cross-piece D³, connecting the guiding-standards, and the other end of the cable is connected to the lever E, pivoted between the upright rods E', which are connected to the bed-plate at the rear of the hood, and the rear end of the lever is pivotally connected to a link-rod F, the lower end of which is connected to a crank-arm G, carried by a rock-shaft H, which is journaled in bearings H', connected to the bed-plate. Another crank-arm I is mounted upon the end of the rock-shaft H, said crank-arm having a pull-lever K connected thereto, said lever resting upon a pin K' and projecting upwardly and forwardly within convenient reach of the operator, the forward end being shaped into a suitable handle or grip K². By pushing down on the lever K the rock-shaft H is turned, throwing the crank-arm G upwardly, which movement forces the forward end of the lever downwardly, thereby pulling upon the cable D and raising the doors B' and C'.

The lever E is provided with a weight E² to assist in this operation, said weight being adjustable. When the doors are raised, the barrel to be heated is placed within the hood, and by reversing the movement of the rod or lever K the doors are closed.

A socket L is rigidly connected to the rock-shaft H and in which is fitted the burner-pipe M, said pipe having an elbow-joint M', and a burner M² is arranged at the extreme end of the pipe. The pipe is of such length that the upwardly-extending end carrying the burner can be projected through the elongated opening A' up into the barrel when the doors of the hood and jacket have been closed, and by connecting the burner-pipe to the rock-shaft H these movements are made simultaneously with the operation of said doors.

N indicates a gas-pipe, which is bent at N' to permit the movement of the burner-pipe, and the said burner-pipe and gas-pipe are connected by means of a flexible pipe O, which leads from a valve O', arranged upon the gas-pipe and operated by means of an arm O², to which is connected a link O³, which link in turn is connected to an angular lever O⁴, rigidly mounted upon the rock-shaft H, so that when said rock-shaft is operated for the purpose of closing the doors and raising the burner the valve O' controlling the supply of gas to the burner-pipe, will be opened and will be closed when the reverse operations take place. A casing P is arranged directly beneath the bed-plate and is made, essentially, V-shaped for the purpose of accommodating the burner and pipe when they are withdrawn from the barrel and hood. This casing is closed on all sides in order to prevent air passing upwardly into the heater, and at the rear

end, where the burner-pipe passes through, I provide a sliding plate P', having an opening P², through which the burner-pipe passes, and this plate slides in guides P³, formed upon the casing, and the plate is of such length that it will effectively close the rear end of the casing when the burner is in either a raised or lowered position. A small air-inlet P³, regulated by a damper, is made in one side of the casing. An igniter-pipe Q has its forward end projected into the casing, projected below the elongated opening A' in the bed-plate and in close proximity to the path of the burner in its upward flight, the purpose of said igniter being to supply the necessary light for lighting the burner as it is moved upwardly into the barrel and hood.

The igniter-pipe Q is connected to the valve Q', which is in communication with the gas-supply pipe N and is operated by an arm Q², link Q³, and angle-lever Q⁴, said angle-lever being rigidly connected to the rock-shaft H. The valves Q' and O' are so constructed with reference to each other that when the shaft H is rocked one valve will be open and the other closed, according to the movement of the said rock-shaft, and when the burner is in its lower position, as shown in dotted lines in Fig. 2, the valve O' is closed and the valve Q' open, so that the igniter is burning and the burner extinguished. As the burner moves upwardly, however, the valve O' opens, gas is supplied to the burner, and in passing close to the igniter the burner becomes lighted and passes upwardly into the hood in the lighted condition, and the igniter-valve Q' is then closed and is not opened again until the burner descends. By means of this construction the use of gas is economized, as no considerable quantity of gas is consumed except when the burner is in operation and used for heating the barrels.

An opening A³ is produced in the top of the hood adjacent the center, and the sliding damper A⁴ is adjustable over said opening for the purpose of regulating the escape of gas and products of combustion. Additional openings A⁵ are produced in the top of the hood adjacent the edges and through which the gas and products of combustion can escape when the damper A⁴ is closed. The jacket C within the hood is not essential and may be dispensed with, if so desired. The burner-pipe N has openings M³ adjacent the rear ends to permit air to enter for the purpose of producing more perfect combustion and a greater heat.

In operation the doors are raised by pushing upon the rod or lever K, and simultaneous with this operation is the lowering of the burner. The barrel is then placed upon the bed-plate over the openings, and by pulling upon the rod the doors are closed and the burner projected upwardly into the barrel to be heated, and as the said burner passes the igniter it will be lighted, as heretofore described.

All of the minor operations of my invention

have been fully described, and further description is not deemed necessary.

Having thus fully described my invention, what I claim as new, and desire to secure by Letters Patent, is—

1. A barrel-heater comprising a bed-plate having an opening therein, a hood arranged upon said bed-plate and having a door, a burner adapted to be projected upwardly through the bed-plate, together with means for simultaneously operating the door of the hood and the burner.
2. A barrel-heater comprising the bed-plate having an opening therein, a hood arranged upon the bed-plate and provided with a door, a burner adapted to be projected upwardly through the opening in the bed-plate, an igniter for lighting said burner, together with means for operating the door of the hood and regulating the valves controlling the supply of gas to the burner and igniter.
3. In a barrel-heater, the combination with the bed-plate having an opening therein, a casing arranged beneath the bed-plate, the swinging burner-pipe adapted to be projected through the opening in the bed-plate, the igniter-pipe, gas-supply pipe, the valves arranged upon said gas-supply pipe and connected with the burner and igniter pipes, the rock-shaft adapted to move the burner-pipe, together with means for connecting the rock-shaft and gas-controlling valves, and means for operating the rock-shaft as set forth.
4. In a barrel-heater, the combination with the bed-plate, of a hood arranged thereon, a jacket arranged within the hood, said hood

and jacket having upwardly-sliding doors, the guiding-standards, the strip connecting the said doors and working between the standards, together with means for raising and lowering the doors, as specified.

5. In a barrel-heater, the combination with the bed-plate, having an opening therein, a casing arranged beneath the bed-plate, a swinging burner-pipe, the sliding plate through which the burner-pipe passes, guides in which the said plate slides, together with means for raising and lowering the burner, as set forth.

6. In a barrel-heater, the combination with the apertured bed-plate, of the hood arranged thereon and having a vertically-sliding door, guiding-standards and connecting cross-pieces, the pulley arranged upon said cross-pieces, the cable connected to the door and passing over the pulley, the lever to which the cord is connected, the rock-shaft and connections between the said rock-shaft and lever, means for operating the rock-shaft, the burner-pipe connected to the rock-shaft, the gas-pipe, the connection between the gas-pipe and burner-pipe, the igniter-pipe, the casing arranged below the bed-plate, and in which the burner-pipe works, valves connected to the gas-pipe, and also to the burner and igniter pipes, together with means operated by the rock-shaft for opening and closing the gas-controlling valves, substantially as set forth.
